UNITED STATES PATENT OFFICE

2,230,720

SNAP ACTION DEVICE

Samuel F. Jarvis, Schenectady, N. Y., assignor to
General Electric Company, a corporation of
New York

Application June 9, 1939, Serial No. 278,257

5 Claims. (Cl. 74—100)

My invention relates to snap action devices, more particularly to snap switches, snap valves and the like and has for its object a simple and reliable device of this character which has but few parts and which is inexpensive to manufacture.

In carrying out my invention I utilize a flat rectangular sheet or strip made of a suitable spring material such as bronze. This strip is preformed 10 with a longitudinal bend along a transverse zone. It is caused to straighten with a snap action by depressing it on one side of the bend. When the pressure is removed, the strip snaps back to its longitudinally bent form.

15 For a more complete understanding of my invention, reference should be had to the accompanying drawing in which Fig. 1 is an elevation view with the casing in section of a manually operated switch embodying my invention; Fig. 2 is a plan view of the device shown in Fig. 1 with the cover removed; Fig. 3 is a sectional view taken along the line 3—3 of Fig. 1; Fig. 4 is a sectional view similar to Fig. 3 but showing the device in its snapped position; Fig. 5 is a fragmentary view in perspective of another form of the device.

20 Referring to the drawing, I have shown my invention in one form as applied to a push button operated switch. A snap action part or element 30 of the device in the form shown consists of a flat rectangular sheet or strip 10 made of a suitable spring metal such as bronze. In a typical device, a strip of bronze about $\frac{3}{4}$ of an inch wide and $\frac{5}{100}$ of an inch thick was used.

35 The strip is bent longitudinally so as to give it a permanent set along a substantially straight zone or bend 11 extending transversely of the strip. Thus the strip consists of two straight flat portions 10a and 10b joined at an angle with each 40 other by the bend 11.

To facilitate the snap action, the strip is mounted in a casing or base 13 having a longitudinal groove or depression 14 in its bottom, and made of a suitable electrically insulating material such as a molded compound. The strip is secured at one end by screws 15 to the bottom of the casing with the sides of one straight portion, as shown the portion 10b, resting on the ledges 16 and 17 at each side of the depression 45 14 so as to be supported by the ledges against distortion downward in a direction substantially transverse to said bend. The other portion 10a of the strip extends upward from the bend 11.

40 A suitable button 18 is provided by means of 50 which pressure can be conveniently applied to

the strip. This button is shown being slidably secured in a cover 19 for the casing. The button furthermore is held by the cover in position to engage the portion 10b of the strip at a point at about its middle transversely of the strip, and 5 preferably, as shown spaced from but near the bend 11. When pressure is removed from the button 18, or more specifically, when the button is permitted to move upward a slight distance to its former position, the portion 10a snaps upward 10 back to its normal position shown in Fig. 1.

When the button is pressed downward, the portion 10b of the strip is bent into a transversely concave shape since the sides are supported by the ledges 16 and 17 in the direction of the pressure applied by the button. More particularly, the sides are supported at opposite points the same distance from the bend as the point of application of pressure by the button. When sufficient pressure is applied the bend 11 suddenly 20 assumes this concave shape whereby the strip is straightened with a snap action, the portion 10a snapping downward to the position 20 indicated by the dotted lines in Fig. 1. In this position, the longitudinal sides of the strip throughout its 25 entire length come to rest on the ledges 16 and 17 as shown in Fig. 4.

While the button 18 must be arranged, for effective snap action, to engage the strip at a point near the bend 11, I have found that much 30 more effective snap action is obtained when the force is applied a short distance from the bend as shown in the drawing. For example, in a typical device having a strip made of bronze spring material about five-thousandths of an inch 35 (.005") thick and three-fourths of an inch ($\frac{3}{4}$ ") wide, pressure applied about one-fourth of an inch ($\frac{1}{4}$ ") from the bend gave a vigorous snap action. Moreover, the movable end of the strip moved only a small amount before the snap action occurred. When pressure was applied directly on the bend 11, however, the movable end moved considerably before the snap action occurred, much less force was required, and the snap action was much less vigorous. Apparently when the force is applied a short distance from the bend, energy is stored in the material by depression of the portion 10b, this energy being released suddenly in effecting the snap action. 45

One advantage of this device is that very little movement of the button 18 is required after it engages the strip to cause the strip to snap. In a typical device, a movement of about $\frac{1}{100}$ of an inch was required. This precision, while inherent in the device, depends of course to a great 50 55

extent upon the construction and relative dimensions of the strip.

It will be understood that the movable end of the strip can be connected to operate suitable mechanism as desired. As shown, a switch contact 21 is secured to the movable end, this contact normally engaging a stationary contact 22 secured on the end of a conductor which projects from the casing 13 to form a terminal 23. To provide for sudden operation of the contacts, i. e., to assure that the movable contact is not disengaged from the stationary contact by any slow preliminary movement of the end of the strip preceding its snap action, the stationary contact 23 is mounted in such a position that it holds the end of the strip depressed to such a point as to give this sudden snap action. Thus if the stationary contact were removed, the strip, as shown in Fig. 1, would assume the dotted line position 24. With the movable end depressed as indicated by the full line position, the movable contact disengages the stationary contact with a snap action and without preliminary slow movement. This furthermore provides for a definite contact pressure between the contacts. Another terminal 25 at the other end of the casing extends into the casing under the end of the strip which is secured to the casing the strip being secured to the casing and to the terminal 25 by the screws 15.

As shown in Fig. 5, the strip 26 is inverted with respect to its support 27 as compared with Fig. 1, the movable end 26a extending downward. Pressure applied by suitable button 28 causes this end to snap upward.

It will be understood that various switching arrangements as well as various mechanisms can be operated by the strip. Thus the movable end may carry a bridging contact or may operate a movable contact between spaced stationary contacts.

While I have shown a particular embodiment of my invention, it will be understood, of course, that I do not wish to be limited thereto, since many modifications may be made and I, therefore, contemplate by the appended claims to cover any such modifications as fall within the true spirit and scope of my invention.

What I claim as new and desire to secure by Letters Patent of the United States is:

1. A snap action device comprising a rectangular strip of thin spring material provided with at least two flat portions joined at an angle with each other by a transverse zone constituting a bend, a support to which one end of said strip is secured, said support being provided with a groove extending lengthwise of said strip defined by ledges engaged by the sides of one portion of

said strip, the other portion of said strip extending at an angle with said support, and means for applying a force to said first portion of said strip at a point spaced from said bend thereby to depress said first portion transversely and cause 5 said bend to assume a curved form whereby said strip straightens with a snap action.

2. A snap action device comprising a substantially flat sheet of spring material permanently bent along a substantially straight zone forming 10 a bend into two substantially flat portions, and means for applying a force to one of said portions at a point spaced from said bend thereby to deform said portion in a direction parallel with said bend and cause said bend suddenly to assume 15 a curved form and said sheet to straighten with a snap action.

3. A snap action device comprising a strip of spring material permanently bent longitudinally along a transverse zone forming a bend into two 20 substantially flat portions, means for supporting opposite sides of one of said portions, and means for applying a force to said portion at a point spaced from said bend thereby to deform said portion transversely and cause said strip to 25 straighten with a snap action.

4. A snap action device comprising a flat rectangular strip of spring material permanently bent longitudinally along a straight transverse zone forming a bend into two straight flat portions, supporting means for said strip engaging points on opposite sides of one of said portions a predetermined distance from said bend and securing said points in at least one direction, and means for applying a force to said portion 35 in said direction at a point between said points of support transversely central of said portion and spaced by said predetermined distance from said bend thereby to deform said portion transversely and cause said bend suddenly to assume 40 a curved form and said strip to straighten with a snap action.

5. A snap-action device comprising a strip of spring material bent longitudinally along a transverse zone forming a bend into two substantially 45 flat portions at an angle with each other, a support to which one end of said strip is secured provided with ledges engaged by the sides of the adjacent portion of said strip, and means for applying a force at a point spaced a predetermined distance from said bend, said force biasing 50 said portion against said ledges thereby to deform said portion transversely and cause said bend suddenly to assume a curved form and said strip to straighten with a snap action.

SAMUEL F. JARVIS.
